LIGHTING FIXTURE

Walter W. Kantack, St. Albans, N. Y., assignor to
 Curtis Lighting, Inc., Chicago, Ill., a corpora-
 tion of Illinois

Application August 3, 1940, Serial No. 359,901

7 Claims. (Cl. 248—78)

This invention relates to lighting fixtures in general, and more especially to lighting fixtures having as a source of light a fluorescent tubular lamp.

Among the objects of the present invention it is aimed to provide an improved lighting fixture including a fluorescent tubular lamp as a source of light, a main base reflector, and a secondary reflector for intercepting the direct light rays from the lamp within the range of normal line of vision and at the same time reflecting the rays of light so intercepted in a generally downward direction.

Another object of the present invention is to provide a lighting fixture including one or more lighting units each of which is characterized by a tubular fluorescent lamp as the source of light, a rear main reflector, and a secondary reflector intercepting the direct rays of light from the lamp in the normal range of vision.

More specifically, it is still another object of the present invention to provide a lighting fixture including a main base plate, also known as a ceiling plate, having brackets and end plates attached thereto, the end plates having means for connecting a main reflector, a secondary reflector and sockets for a fluorescent tubular lamp.

These and other features, capabilities and advantages of the invention will appear from specific embodiments thereof illustrated in the accompanying drawings, in which

Figure 1 is a diagrammatic transverse sectional elevation illustrating one form of my invention;

Fig. 2 is a diagrammatic transverse sectional elevation illustrating a modification of Fig. 1;

Fig. 3 is a transverse sectional elevation illustrating the embodiment disclosed in Fig. 2, as a commercially manufactured article;

Fig. 4 is a bottom plan view of Fig. 3;

Fig. 5 is a perspective elevation partly broken away, illustrating a method of providing variable lengths of fixtures;

Fig. 6 is a side elevation partly in section of Fig. 5;

Fig. 7 is a bottom plan view of a rectangular form of fixture;

Fig. 8 is a section on line 8—8 of Fig. 7;

Fig. 9 is a transverse section illustrating light intercepting louvers; and

Fig. 10 is a detail view on the line 10—10 of Fig. 9.

The embodiment diagrammatically disclosed in Figure 1 shows a top wall 1 and side wall 2, and a main reflector 3, including in the present

instance, three reflecting elements 4, 5 and 6. The element 4 consists of a polygonal face approaching an arc, including in the present instance, the faces 6, 7, 8 and 9. The reflecting element 5 reflects the light rays received by it from the fluorescent tubular lamp 10 upwardly against the reflecting element 4, which in turn bends these rays, and also the light rays which it receives directly from the fluorescent tubular lamp 10 outwardly and downwardly. The horizontal axis of the lamp 10 as shown in this embodiment, is substantially ten degrees below the upper edge of the reflecting element 5 and substantially twenty degrees above the lower edge of this reflecting element 5. The reflecting element 6 directs such rays of the lamp 10 which it receives in a generally downward and outward direction. This main reflector 3 cooperates with the secondary reflector 11 in the present embodiment, to direct generally downward about forty per cent of the light rays of the lamp 10 in order to cause the remaining sixty per cent of the light rays to be directed upwardly, outwardly and downwardly to produce what is generally termed indirect lighting. More specifically, the reflector 11 in the present instance consists of two reflecting elements 12 and 13, the reflecting element 12 directing upwardly toward the reflecting element 4, the light rays which it receives from the lamp 10, and the reflecting element 13 reflecting downwardly and inwardly all rays which it receives from the lamp 10. The lower edge of the reflecting element 12 in the present instance is substantially fifteen degrees below the horizontal axis of the lamp 10, and the upper edge of this reflecting element 12 is substantially twenty degrees above the horizontal axis of the lamp 10 and just below the upper level of the lamp 10.

The intersection between the reflecting elements 5 and 6, similarly the intersection between the reflecting elements 12 and 13, and the inclination of the reflecting elements 7, 8, 9, 5, 6, 12 and 13, are so arranged as will clearly appear from Fig. 1, that substantially none of the light rays from the lamp 10 are directed back at the lamp itself. This is particularly significant and of value in view of the density of the tube 10, the inner face of which, in the common practice today in use, consists of a coating of opaque fluorescent salts.

In the embodiment diagrammatically illustrated in Fig. 2, there is provided a top wall 14, a side wall 15, a main reflector 16, and a secondary reflector 17, all substantially vertical to an imaginary plane with a fluorescent tubular lamp

18 disposed intermediate the main reflector 16 and secondary reflector 17, the longitudinal axis of which is similarly perpendicular to the imaginary vertical plane aforesaid.

The combination here diagrammatically disclosed, as distinguished from the combination disclosed in Fig. 1, while similarly using the secondary reflector to intercept the direct light rays from the normal range of vision, and being in a plane extending away from the surface of the lamp directs downwardly and outwardly about sixty per cent of the effective light rays of the lamp 18 and the remaining forty per cent of the effective light rays upwardly to cooperate with the upper portion of the reflector 16 to produce what is generally known as indirect lighting.

The reflector 16 in the present instance, consists of two main portions, one portion including the arcuate reflecting elements 19 and 20, and the other portion including the arcuate reflecting elements 21 and 22. The reflecting elements 19 and 20 extend down to the point 23, which point is substantially thirty degrees above the horizontal axis of the lamp 18, serve mainly to produce, as indirect light rays, the light rays received from the lamp 18. The reflecting elements 21 and 22 below the point 23 serve mainly to direct downwardly and outwardly the light rays received by them from the lamp 18.

The reflector 17 consists essentially of the reflecting faces 24 and 25 sufficiently oblique to the adjacent surface of lamp 18 to direct downwardly and inwardly the light rays received by them from the lamp 18. The upper edge of the reflecting element 24 is substantially thirty degrees above the horizontal axis of the lamp 18 and slightly below the upper level of the lamp 18. The lower edge of the reflecting face 24 is substantially in line with the horizontal axis of the lamp 18. It should here also be noted that the inclinations of the several reflecting faces 19, 20, 21, 22, 24 and 25 relative to the lamp 18 are such as noted with regard to the embodiment illustrated in Fig. 1, that they will reflect back upon the lamp 18 substantially none of the light rays received by them, and for the purpose noted with regard to the embodiment illustrated in Fig. 1.

The embodiments illustrated in Figs. 1 and 2 indicate how this combination of main reflector, secondary reflector, and fluorescent tubular lamp may be adjusted one to the other to obtain either a greater or less amount of indirect lighting, and still preserve intercepting the direct light rays from the normal line of vision.

Carrying out these embodiments commercially, the embodiment illustrated in Figs. 3 and 4 is an example.

Here there is illustrated a sheet metal top cover or ceiling plate 26 which in the present instance may be connected to the ceiling 27 by any suitable means such for instance as the expansion bolts 28. To this plate 26, as shop assembled, there is preferably connected at each end thereof an end plate 29. These end plates 29 have inwardly extending lugs 30, 31 and 32 through which extend screws 33 connecting the lugs and thereby the end plates 29 to the top plate 26. The end plates 29 also have inwardly extending lugs 34 to which is connected the molding 35. The molding 35 preferably has at its ends straps 36 having screw threaded openings 37 to receive the screws 38 extending from the inside of the lugs 34, through the lugs 34 into screw threaded engagement with the tapped

holes 37 in the straps 36. The molding 35 extends from one end plate 29 to the other. Also, as part of the shop assembled unit, there are connected the brackets 39 and 40 which have webs 41 riveted to the top plate 26 and inclined wings 42, the wings 42 of the brackets 39 and 40 of a pair being inclined toward one another. To the inclined wings 42, as shop assembled, there are secured the sockets 43 having the enlarged portions 44 secured to the inner faces of the wings 42 and the extensions 45 extending outwardly of the sides of the wings 42. Also, as shop assembled, the top plate 26 preferably has connected thereto the moldings 46 and 47 which extend the full length of a unit between the end plates 29 as shown in Fig. 4, being connected to the top plate 26 by screws 48.

When the lighting fixture is installed, the shop assembled unit as aforesaid is preferably connected to the ceiling 27 by the expansion bolts 28 as shown, and thereupon the main reflectors 49 and 50, each extending the full length of a unit between the inner faces of the end plates 29 being slotted to clear the extensions 45 of the sockets 43, are put in place and connected to the wings 42 of the brackets 39 and 40 by means of suitable screws or the like. Thereupon, the secondary reflectors 51 and 52 are connected to the lugs 53 and 54, extending from the inner faces of the end plates 29 by means of the screws 55 and 56 respectively. The secondary reflectors 51 and 52 similarly extend the full length of a unit from the one inner face to the other inner face of the end plates 29. After the reflectors are so assembled, then the fluorescent tubular lamp 57, such for instance as the 40-watt one and one-half inch diameter, four foot long fluorescent tube generally used in practice, is connected to the extensions 45 of the sockets 43 in the usual way. The electrical connection and equipment necessary with fluorescent tubular lamps are mounted within the enclosure formed by the top plate 26 and reflectors 49 and 50. Access to this electrical equipment in the chamber so formed between the top plate 26 and reflectors 49 and 50 is readily afforded by the ready removability of the lamps 57, and reflectors 49, 50, 51 and 52.

The position of the reflectors 49 and 50 are predetermined. As an instance, the outer edge 58 of the reflector 49 engages the flange 59 of the moulding 46 extending the full length of a unit, and the inner edge 60 engages the flange 61 of the molding 35. When the lamps 57 and reflectors 49, 50, 51 and 52 are so removed, the basic supporting structure remains intact as a rigid structure consisting of the top plate 26, end plates 29, and moldings 46, 47 and 35.

When the universally popular length of the lamp 57 as aforesaid, four feet, is used, obviously the units will be substantially four feet in length. Obviously, the lengths of these units may be varied according to requirements without departing from the main object of the invention.

In the embodiment illustrated in Figs. 5 and 6, in place of an end plate 29 at the end of the first unit 62, a connecting plate 63 may be substituted to facilitate attaching a second unit 64 to the first unit 62 and thus increasing the length of the lamp fixture substantially at will. In such case, the connecting plate 63 has lugs such as the lugs 30, 31, 32, 53, 54 and 34 extending from both faces thereof, corresponding in position to the position of these lugs on the plate 29.

As shown in Fig. 3, the end plates are recessed

between the end portions 65 and 66 so that the end plates will only engage the ceiling at the ends thereof. The upper edges of the moldings 46 and 47 are spaced from the upper edges of the projections 65 and 66 so that they will definitely clear the ceiling throughout the length of the lighting fixture.

It is obvious that the unit illustrated in Fig. 3 consists of two units such as diagrammatically illustrated in Fig. 2.

Figs. 7 and 8 show a still further development of multiplying the unit diagrammatically illustrated in Fig. 1, it consisting of a rectangular lighting fixture 67 composed of four main lighting units 68, 69, 70 and 71 connected to one another by mitered ends 72, the end plates 29a being obliquely disposed and forming the corner. Each of these main units 68, 69, 70 and 71 in turn include two units 73 and 74 similar to the single unit diagrammatically illustrated in Fig. 1, and are disposed with their backs toward each other to face in opposite directions. Corner plates 90 assist in uniting the proximate end portions of the longitudinal and transverse units, said plates 90 also provide a decorative finish which presents a neat appearance to the observer. The main reflectors, which are of a generally concave shape in cross-section, are disposed to face downward and are, as before explained, each formed in the quadrant of a circle to one side of a vertically extending diameter. Each of the units is provided with the top plate 26 and the longitudinally disposed moulding strips 46 and 47 are carried by these top plates and are engaged by the adjacent upper margins of the main reflectors. The secondary reflectors 12-13 are disposed in front of the lamps 10 and they are preferably oblique to the main reflectors upon the opposite sides of the lamps. The lower portions of these units are opened, as will be understood by reference to Figure 1, except at the junction by the adjacent units where the corner plates 90 are mounted. In this arrangement a said proportion of the light waves are directed in a downward and outward direction, and another proportion of the light waves are directed upwardly for indirect illumination.

From the foregoing basic disclosures, it will be apparent that combinations of these structures can be evolved which will lend themselves to being mounted flush on the ceiling in linear or rectangular form or pendant in similar forms, and also to be mounted where a single lamp is used in the assembly along the walls and ceilings of rooms in either continuous or intermittent variation.

Due to the length of the fluorescent tubular lamps, especially when four feet long, in order to intercept the direct light rays from the lamp in the normal range of vision, that is, directed longitudinally with or approaching a direction longitudinally with the axis of the lamp, it is preferable to provide intercepting devices. In the present instance, one form of these intercepting devices, see Figs. 9 and 10, consists of a plurality of louvers which would be spaced from one another so as to provide approximately forty degrees coverage. These louvers consist of two main wings 80 and 81 with an intermediate connecting arm 82 which are provided with recesses 83 to receive the rod 84 connected at its ends to lugs formed at the lower ends of the end plates 29. As braces or alining elements, the wings are also notched at their upper ends directly below the lamps 57 as at 85 and 86. The successive

wings 80 of one group are mounted upon a bracing or alining rod 87 which is also slotted in a well known manner to cooperate with the slots 85 of the wings 80, and secured in position by staking. Similarly, a rod 88 provided with slots to cooperate with the slots 86 of the wings 81 is provided which is similarly secured to the wings 81 by staking. The rod 84 is also slotted and preferably connected to the arms 82 by staking.

When thus assembled, these louver shields constitute a unit easily handled and readily installed and removed.

It is obvious that various changes and modifications may be made to the construction without departing from the general spirit of the invention as set forth in the appended claims.

I claim:

1. The combination of a rectangular four-element lighting fixture, each element including a pair of horizontally extending main concave reflectors facing downwardly and outwardly away from one another in adjacent quadrants of circles, each quadrant being disposed to one side of a vertically extending diameter, a tubular lamp for each main reflector, each lamp extending horizontally in front of each main reflector and well within the respective quadrant, a horizontally extending secondary reflector facing each lamp and well within the quadrant of its associated main reflector and positioned to intercept the direct light rays from its associated lamp in the normal range of vision, said reflectors positioned to direct light rays outwardly from the unit whereby a proportion of the rays pass downwardly and another proportion thereof pass upwardly for indirect illumination; and means for operatively connecting said reflectors and lamps in the positions named.

2. The combination of a multiple-unit luminaire wherein the units are disposed in a hollow form about a common center, each said unit embodying a horizontally extending main concave reflector facing downwardly and outwardly and formed in the quadrant of a circle to one side of a vertically extending diameter; a tubular lamp for said main reflector, said lamp extending horizontally in front of and intermediate the upper and lower margins of said main reflector and well within said quadrant; said main reflector having a portion extended above said lamp and disposed with its margin overhanging said lamp to reflect light rays outwardly in both upward and downward directions; a horizontally extending secondary reflector facing said lamp and main reflector and well within said quadrant and positioned to intercept the direct light rays from said lamp in the normal range of vision; said main and secondary reflectors having lower portions disposed below said lamp and diverging downwardly to reflect light rays outwardly in a downward direction; means for operatively connecting said reflectors and lamp in the positions named; and means connecting the proximate ends of a plurality of said units about a common center.

3. The combination of a multiple-unit luminaire wherein the units are disposed in a hollow form about a common center, each said unit embodying a pair of horizontally extending main concave reflectors facing downwardly and outwardly away from one another and formed in adjacent quadrants of circles, each quadrant being disposed to one side of a vertically extending diameter, a tubular lamp for each main reflector, each lamp extending horizontally in front

of and intermediate the ends of its main reflector and well within the quadrant of its main reflector; a horizontally extending secondary reflector in front of and facing each lamp and each main reflector and well within the quadrant of its associated main reflector, said secondary reflectors positioned to intercept the direct light rays from their respective lamps in the normal range of vision on each side of the unit; said reflectors positioned to direct light rays outwardly from the unit whereby a proportion of the rays pass downwardly and another proportion thereof pass upwardly for indirect illumination; means operatively connecting said reflectors and lamps in the positions named; and means connecting the proximate ends of a plurality of said units about a common center.

4. The combination of a multiple-unit luminaire wherein the units are disposed in a hollow form about a common center, each unit embodying a horizontal top-plate; end plates connected thereto; a horizontally extending main concave reflector facing downwardly and outwardly and formed in the quadrant of a circle to one side of a vertically extending diameter, said reflector disposed between said end plates and below said top-plate; a tubular lamp for said main reflector, said lamp extending horizontally in front of and intermediate the upper and lower margins of said main reflector and well within said quadrant; said main reflector having a portion extended above said lamp and disposed with its margin overhanging said lamp to reflect light rays outwardly in both upward and downward directions; a horizontally extending secondary reflector facing said lamp and main reflector and well within said quadrant and adapted to intercept the direct light rays from said lamp in the normal range of vision, said secondary reflector connected at its ends to said end plates; said main and secondary reflectors having lower portions disposed below said lamp and diverging downwardly to reflect light rays outwardly in a downward direction; and means for operatively connecting a plurality of units about a common center.

5. A luminaire comprising a plurality of longitudinal and transverse units formed into a hollow rectangle, each unit providing a side thereof and embodying a horizontal top-plate; end plates at the corners of the rectangle and connected to said top-plate; a horizontally extending main concave reflector facing downwardly and outwardly and formed in the quadrant of a circle to one side of a vertically extending diameter, said reflector disposed between said end plates and below said top-plate; a tubular lamp for said main reflector, said lamp extending horizontally in front of and intermediate the upper and lower margins of said main reflector and well within said quadrant; said main reflector having a portion extending above said lamp and disposed with its margin overhanging said lamp to reflect light rays in both upward and downward directions; a horizontally extending secondary reflector facing said lamp and said main reflector and well within said quadrant and adapted to intercept the direct light rays from

said lamp in the normal range of vision, said secondary reflector connected at its ends to said end-plates; said main and secondary reflectors having lower portions disposed below said lamp and diverging downwardly to reflect light rays outwardly in a downward direction; and means for operatively connecting the proximate ends of said longitudinal and transverse units about a common center.

10 6. A luminaire comprising a plurality of longitudinal and transverse units formed into a hollow rectangle, each unit providing a side thereof and embodying a horizontal top-plate; end plates at the corners of the rectangle and connected to said top plate; a pair of horizontally extending main concave reflectors facing downwardly and outwardly away from one another and formed in adjacent quadrants of circles, each quadrant being disposed to one side of a vertically extending diameter, said reflectors disposed between said end plates and below said top-plate; a tubular lamp for each main reflector, each lamp extending horizontally in front of and intermediate the ends of its main reflector and well within the quadrant of its main reflector; a horizontally extending secondary reflector in front of and facing each lamp and each main reflector and well within the quadrant of its associated main reflector, said secondary reflectors positioned to intercept the direct light rays from their respective lamps in the normal range of vision on each side of the unit; said reflectors positioned to direct light rays outwardly from the unit whereby a proportion of the rays pass downwardly and another proportion thereof pass upwardly for indirect illumination; means operatively connecting the reflectors and lamps of a unit in the positions named; and means connecting the proximate ends of said longitudinal and transverse units about a common center.

7. The combination of a multiple-unit luminaire wherein the units are disposed about a common center, each said unit embodying a horizontally extending main concave reflector facing downwardly and outwardly and formed in the quadrant of a circle to one side of a vertically extending diameter; a tubular lamp for said main reflector, said lamp extending horizontally in front of and intermediate the ends of said main reflector and well within said quadrant; a horizontally extending secondary reflector facing said lamp and well within said quadrant and positioned to intercept the direct light rays from said lamp in the normal range of vision; said first-mentioned main reflector and said secondary reflector positioned in inclined relation to one another and tangent to said lamp whereby to direct a proportion of the light rays in a downward and outward direction and also to direct another proportion of the light rays in an upward and outward direction for indirect illumination; means for operatively connecting said reflectors and lamp in the positions named; and means connecting the proximate ends of a plurality of said units about a common center.

WALTER W. KANTACK.
